(57) CLAIM

The ornamental design for an artificial eyelash tray, as shown and described.

DESCRIPTION

FIG. 1 is a perspective view of an artificial eyelash tray showing our new design;

FIG. 2 is a front elevational view thereof;

FIG. 3 is a back elevational view thereof;

FIG. 4 is a first side elevational view thereof;

FIG. 5 is a second side elevational view thereof, opposite said first side;

FIG. 6 is a top view thereof; and,

FIG. 7 is a bottom view thereof.

The elements shown in broken lines depict environmental structure only and form no part of the claimed design.
